CEMENTING BAILER.

Application filed March 10, 1926. Serial No. 93,627.

This invention is a dump bailer for cementing a well, and it is the object of the invention to open the bailer for discharging cement at any desired level in a well, and to 5 positively lock the bailer in open position so as to prevent closing thereof when it is withdrawn from the well and thereby insure discharge of all of the cement.

It is a further object of the invention to 10 open the bailer by telescoping a sleeve through abutment of an impact member against the bottom of the well bore so as to align ports in the sleeve and bailer for discharge of cement, the sleeve being normally 15 extended on the bailer for non-alinement of the ports so as to close the bailer and prevent discharge of any cement until abutment of the impact member telescopes the sleeve to its limit of movement.

It is a still further object of the invention 20 to provide a locking connection between the impact member and bailer adapted to automatically engage when the sleeve is telescoped its full distance, thereby positively 25 retaining the bailer in open position during subsequent withdrawal from the well.

The invention will be readily understood 30 from the following description of the accompanying drawings, in which:

Fig. 1 is an axial section through a well bore showing the cementing bailer in closed position.

Fig. 2 is a similar view showing the cementing bailer open for discharge of cement.

Fig. 3 is a fragmentary elevation at right angles to Fig. 1 and showing the cementing bailer closed.

The cementing bailer is employed in a usual deep well A adapted to receive the 40 string of casing 1, the casing being elevated slightly when the well is to be cemented, so that the casing shoe 2 is above the bottom of the well to permit cement to flow from the casing and upwardly between the same and the bore.

The dump bailer for the cement may be lowered into the casing and withdrawn by any usual means, shown in the present instance as a string of tubing 3 adapted for 50 suspension of the bailer therefrom by a usual threaded connection 5.

The threaded connection 5 is provided at the upper end of a section of pipe 4 which forms the bailer proper; and this pipe is 55 closed in spaced relation above its lower end

by a transverse partition 15, so that when the ports 17 in the sides of the pipe above the partition are opened, cement is discharged from the bailer into the well casing.

A sleeve 14 is slidable on pipe 4 and is 60 limited in its downward movement by abutment against a collar 6 which is threaded onto the lower end of pipe 4 as shown at 7. Parts 16 are provided in the sides of sleeve 14 and are adapted to align with ports 17 65 for discharge of cement when the sleeve is elevated on pipe 4, but are below the ports 17 when the sleeve is at its normal lower limit of movement in order to shut off discharge of cement.

The sleeve 14 is elevated on pipe 4 from 70 normal closed position shown in Fig. 1, by an impact rod 8 telescoping in the lower end of pipe 4 below partition 15 and having a head 9 forming an undercut shoulder 75 10 which rests upon a flange of collar 6 for limiting extension of the impact rod relative to the bailer pipe.

The telescoping rod is fixed to sleeve 14 80 by studs 12 which project through axial slots 13 in pipe 4, the slot and stud connection maintaining the ports 16-17 in longitudinal alinement and limiting elevation of sleeve 14 so as to exactly align the ports.

As the bailer is lowered in a well, the weight of rod 8 extends the same below pipe 4 so as to lower sleeve 14 and close ports 17, and when the impact rod strikes the bottom of the well continued lowering of the bailer 90 telescopes the impact rod in pipe 4 and thereby elevates sleeve 14 to align ports 16-17 and thereby discharge the cement from the bailer. A coupling 11 is preferably provided at the lower end of rod 8 so that an 95 extension B may be connected thereto if desired, for abutment of the impact member against the bottom of the well bore when the bailer is at any desired level as determined by the length of the extension B. 100

When the impact rod telescopes in pipe 4 so as to open the cement discharge ports, the parts are automatically locked to prevent closing of the ports 17 when the bailer is 105 subsequently withdrawn. As an instance of this arrangement a latch 18 projects from rod 8 and is adapted for retraction as it passes the flanged collar 6; and when the rod 8 is fully telescoped so as to open ports 17, the latch is above the flanged collar and 110

is again projected so as to seat on the flange of the collar for preventing relative movement between the impact rod and the bailer pipe.

5 The latch 18 is preferably yieldably projected by a spring 21 mounted in the transverse bore 19 in which the latch slides, the spring being held in place by a screw plug 22 and engaging a guide head 20 at the inner 10 end of the latch.

Projection of the latch is preferably limited by abutment of its head 20 against a shoulder formed by the bore 19, in order to prevent displacement of the latch from the 15 rod 8.

After the bailer has been withdrawn from the well with the ports 17 maintained in open position by the locking engagement of latch 18, the latch may be retracted to per-

20 mit return of the parts to normal position with ports 17 closed, by inserting a suitable tool in an aperture 23 which extends through collar 6 in alinement with latch 18.

25 The improved construction thus provides a normally closed bailer which will not open for discharge of cement until the impact member is telescoped to its limit of movement; and as a consequent there is no possibility of accidental discharge of cement 30 through slight telescoping of the impact member as a result of striking an obstruction in the well.

35 The invention also provides for positively locking the bailer in its open position to insure discharge of all of the cement as the bailer is subsequently withdrawn from a well.

We claim:

40 1. A dump bailer comprising a pipe having a transverse partition and a discharge port in the pipe above the partition, an exterior and an interior abutment surface at the lower end of the pipe, a sleeve slidable on the pipe and normally resting on the exterior abutment surface, said sleeve having a port in non-alinement with the discharge port and below the partition for closing the discharge port when the sleeve is in normal position, an impact member slidable in and 45 projecting beyond the lower end of the pipe below the partition and normally extended relative to the pipe, a shoulder on said member engaging the interior abutment surface for limiting normal projection of the impact member, the lower end of the pipe being slotted, and pins slidably in said slots connecting the impact member and the sleeve for raising the sleeve on the pipe by telescoping of the impact member in the lower 50 end of the pipe to aline the sleeve port with the discharge port so as to open the discharge port.

2. A dump bailer comprising a pipe having a transverse partition and a discharge port in the pipe above the partition, a sleeve 65 slidable on the pipe and having a port in non-alinement with the discharge port and below the partition for closing the discharge port when the sleeve is in normal position, an impact member slidable in and normally 70 extended beyond the lower end of the pipe below the partition, the lower end of the pipe being slotted, and a connection between the impact member and the sleeve slidable in the slot for raising the sleeve on the pipe 75 by telescoping of the impact member in the lower end of the pipe to aline the sleeve port with the discharge port so as to open the discharge port.

3. A dump bailer comprising a pipe having a transverse partition and a discharge port in the pipe above the partition, a sleeve 80 slidable on the pipe and having a port in non-alinement with the discharge port when the sleeve is in normal position, an impact 85 member slidable in and normally extended beyond the lower end of the pipe below the partition, the lower end of the pipe being slotted, a connection between the impact member and the sleeve slidable in the slot 90 for raising the sleeve on the pipe by telescoping of the impact member in the lower end of the pipe to aline the sleeve port with the discharge port, and cooperating means on the impact member and the lower end 95 of the pipe below the partition for automatically locking the impact member in telescoped position.

4. A dump bailer comprising a pipe having a transverse partition and a discharge 100 port in the pipe above the partition, a sleeve slidable on the pipe and having a port in non-alinement with the discharge port when the sleeve is in normal position, an impact member slidable in and normally extended 105 beyond the lower end of the pipe below the partition, the lower end of the pipe being slotted, a connection between the impact member and the sleeve slidable in the slot 110 for raising the sleeve on the pipe by telescoping of the impact member in the lower end of the pipe to aline the sleeve port with the discharge port, an interior flange on the lower end of the pipe, and a yieldable projecting latch on the impact member adapted 115 to automatically engage the flange for locking the impact member in telescoping position.

In testimony whereof they have affixed their signatures to this specification.
